US0D1013080S

(12) **United States Design Patent** (10) Patent No.: **US D1,013,080 S**
(45) Date of Patent: ** *Jan. 30, 2024

(54) **TWO WHEELED BOARD**(71) Applicant: **RAZOR USA LLC**, Cerritos, CA (US)(72) Inventor: **Ian Desberg**, Cerritos, CA (US)(73) Assignee: **Razor USA LLC**, Cerritos, CA (US)

(*) Notice: This patent is subject to a terminal disclaimer.

(**) Term: **15 Years**(21) Appl. No.: **29/824,133**(22) Filed: **Jan. 21, 2022**

CLAIM

The ornamental design for a two wheeled board, as shown and described.

DESCRIPTION

FIG. 1 is a front, top, left-side perspective view of a two wheeled board of my design;

FIG. 2 is a rear, bottom, left-side perspective view thereof;

FIG. 3 is a top view thereof;

FIG. 4 is a bottom view thereof;

FIG. 5 is a front view thereof;

FIG. 6 is a rear view thereof;

FIG. 7 is a left-side view thereof; and,
FIG. 8 is a right-side view thereof.

The dashed lines illustrate portions of the two wheeled board
that form no part of the claim. The dash-dot lines represent
bounds of the claim. None of the dashed lines form a part of
the claimed design.

1 Claim, 7 Drawing Sheets
